INSECT REPELLENT

William A. Simanton, Pittsburgh, Pa., assignor to
 Gulf Research & Development Company, Pittsburgh, Pa., a corporation of Delaware

No Drawing. Application March 16, 1936,
 Serial No. 69,218

6 Claims. (Cl. 167—22)

This invention relates to insect repellents and more particularly it relates to an improved insect repellent comprising a petroleum fraction containing an added substance selected from the 5 class consisting of diethylene glycol monobutyl ether and diethylene glycol monoethyl ether acetate; and it further comprises a method of manufacturing such a repellent; all as more fully hereinafter set forth and as claimed.

10 Insect repellents differ from insecticides in that they are not particularly toxic to insects and for the most part they employ a petroleum base to which something is added repulsive to insects. In order to give a composition of a particular 15 consistency for a particular use, the consistency of both the base and of the addition must be considered. For instance, when the repellent is to be made up in the form of a spray, either an extremely light lubricating oil or a petroleum naphtha forms the base. On the other hand, 20 when it is desired to impart a salve-like consistency to the repellent, the petroleum base employed is usually a petroleum jelly such as petrolatum or an unctuous solution of a petroleum 25 wax. If a repellent is to be used in the form of a lotion a petroleum fraction is used which in viscosity is somewhere intermediate between those mentioned above, such as a white petroleum oil of the variety usually known as medicinal oils.

30 In the past, pine oil has been considered one of the better insect repellents suitable for incorporation in petroleum bases. However, this compound is objectionable by reason of its strong odor which is offensive not only to insects but to human beings. When used in repellents applied 35 to dairy cattle, pine oil frequently taints the milk and thus ruins it for human consumption.

I have discovered that diethylene glycol monobutyl ether and diethylene glycol monoethyl ether acetate are excellent insect repellents having certain advantages over prior repellents when incorporated in petroleum bases. Both are practically odorless and both are sufficiently soluble in petroleum oils for the present purposes. 40 These compounds when incorporated in petroleum bases are substantially odorless in concentrations up to 15 per cent. Repellence towards flies and other insects is definitely exhibited when either of these compounds is present in petroleum 45 base preparations in concentrations of 5 per cent or over.

I find that diethylene glycol monobutyl ether is more soluble in heavy oils, jellies and waxes than is diethylene glycol monoethyl ether acetate 50 and this property makes it more suitable for

incorporation with heavier petroleum fractions. However, diethylene glycol monoethyl ether acetate is sufficiently soluble in light oils to make its use advantageous when the repellent composition is to be given the consistency of a liquid lotion or 5 a liquid spray. For instance, diethylene glycol monoethyl ether acetate is soluble up to 5 per cent by volume in petroleum oils having a viscosity of 100 at 100° F. as determined with the Saybolt universal viscosimeter. Diethylene glycol monobutyl ether is entirely miscible with petroleum oils having a viscosity of 100 S. U. V. at 100° F. and it is soluble in petroleum jellies such as petrolatum in concentrations of 15 per cent by volume or over. In soft petroleum waxes 10 it is slightly less soluble, but sufficient amounts may be incorporated with such waxes to impart a definite repellence to the mixture.

In an advantageous embodiment of my invention I have prepared an excellent repellent spray 20 particularly suitable for application to livestock by adding 8 per cent by volume of diethylene glycol monobutyl ether to a highly refined light spindle oil having a viscosity of 55 sec. at 100° F. as determined by the Saybolt universal viscosimeter. The repellent so prepared will maintain 25 repellence towards stable flies, horn flies and other insects after spraying for as long a time as sprays containing similar concentrations of pine oil and is substantially odorless and will not taint 30 milk when applied to dairy cattle.

In another embodiment of my invention I have prepared an excellent repellent salve by adding 15 per cent by volume of diethylene glycol monobutyl ether to commercial petrolatum and thoroughly mixing the mass until it becomes homogeneous. The salve so prepared will maintain 35 repellence towards flies quite as long as salves containing similar concentrations of pine oil. In addition my salve as prepared above is substantially odorless and possesses a decidedly unpleasant taste which discourages animals from licking 40 areas to which the salve has been applied.

I find that in accordance with my invention an excellent insect repellent spray for household use may be manufactured by adding between 5 and 15 per cent of either diethylene glycol monobutyl ether or diethylene glycol monoethyl ether acetate to a light petroleum naphtha which has been refined sufficiently to make it odorless. In use 45 such a spray is inoffensive to human beings, but is decidedly effective in keeping away many species of insects.

My invention is not limited to petroleum base 50 preparations in which diethylene glycol mono-

butyl ether and diethylene glycol monoethyl ether acetate are the only ingredients. For instance, in some insecticides like live stock sprays it is desirable to have in petroleum solutions toxic ingredients as well as those exhibiting repellence towards insects. Petroleum base preparations containing pyrethrins or other toxicants can be readily incorporated into my composition which also has a petroleum base. Such use is contemplated.

The invention is not to be considered as limited to the foregoing examples as these are by way of illustration only.

What I claim is:—

- 15 1. A petroleum fraction containing between 5 and 15 per cent of a substance selected from the class consisting of diethylene glycol monobutyl ether and diethylene glycol monoethyl ether acetate as an insect repellent.
- 20 2. A petroleum fraction containing between 5

and 15 per cent of diethylene glycol monobutyl ether as an insect repellent.

3. A petroleum jelly containing between 5 and 15 per cent of diethylene glycol monobutyl ether as a repellent.

4. The subject matter of claim 1, wherein said petroleum fraction is a light spindle oil.

5. The subject matter of claim 2, wherein said petroleum fraction is a light spindle oil.

6. As a new composition of matter of odorless 10 character having strong insect repellent qualities, a solution in a petroleum fraction of between 5 and 15 per cent of an odorless substance chosen from the class consisting of diethylene glycol monobutyl ether and diethylene glycol monoethyl 15 ether acetate, the petroleum fraction having sufficient solvent power for said substance to make a clear solution with the amount added.

WILLIAM A. SIMANTON.
